UNITED STATES PATENT OFFICE.

CHARLES W. SLEEPER, OF LANCASTER, NEW HAMPSHIRE, ASSIGNOR, BY MESNE ASSIGNMENTS, TO AMERICAN KEY CAN COMPANY, OF CHICAGO, ILLINOIS, A CORPORATION OF NEW JERSEY.

FLANGING-MACHINE.

No. 805,429.

Specification of Letters Patent.

Patented Nov. 21, 1905.

Application filed January 29, 1903. Renewed March 4, 1904. Serial No. 196,489.

To all whom it may concern:

Be it known that I, CHARLES W. SLEEPER, a subject of His Majesty the King of Great Britain, and a resident of Lancaster, in the county of Coos and State of New Hampshire, have invented certain new and useful Improvements in Flanging-Machines, of which the following is a specification.

My invention relates to improvements in mechanism for flanging cans, which is the process of turning a portion of the end of a can-body outward or inward at an angle with the axis of the can.

The machine shown and described is especially designed to turn the flanges outward upon both ends of a so-called "square" can. It is obvious, however, that by changing the shape of the dies the machine may be used for flanging cans of other shapes upon one or both ends.

Figure 1 is a front elevation of my machine. Fig. 2 is an elevation of the right side. Fig. 3 is an elevation of the left side. Fig. 4 is a top view. Fig. 5 is a detail showing the top of the table and the feed-chain. Fig. 6 is a top view, and Fig. 6^a a side view, of the chuck C with its jaws closed. Fig. 7 is a top view, and Fig. 7^a a side view, of the chuck C with its jaws open. Fig. 8 is a front view, and Fig. 8^a a side view, of the mechanism for raising the bottom die. Fig. 9 is a side view of the gate B. Fig. 10 is a top view of the gate B, showing the same closed. Fig. 11 is a top view of the gate B, showing the same opened. Figs. 12 and 13 are details showing the action of the dies. Fig. 14 is a side elevation of a can-body after the same is flanged. Fig. 15 is a side and a plan view of a stripper g. Fig. 16 is a plan view of the yoke g' and strippers g. Fig. 17 is a group of details showing the crank-pinion c² and sliding block c⁴. Fig. 18 is a top and a side view of the jaws c. Fig. 19 is a side view of the cam d and cam-rod d' with the parts connected therewith.

45 A is the frame of the machine.
A' is the table.

A² is a driving-shaft provided with a friction clutch-pulley A³ and means for operating the same.

50 A⁴ is a spur-pinion on the shaft A², engaging a gear A⁵ upon the crank-shaft A⁶.

A⁷ is a connecting-rod adjustably connect-

ing the crank A⁶ with the ram A⁸, which is suitably guided in the face of the frame A.

A chain a connects a sprocket-wheel a' upon the shaft A⁶ with a similar wheel a³ upon a shaft a⁴, which also carries a barrel-cam a⁵, engaging suitable rollers a⁶ a⁶ upon the side of the feed-chain a⁷, which passes over idle wheels a⁸ a⁸ and rests upon the feed-tables a⁹ a¹⁰. The cam a⁵ gives intermittent progressive motion to the chain a⁷ with periods of rest equal to about twice the periods of motion. The links of the chain a⁷ are large enough to allow the can-body to drop loosely into them and rest upon the tables a⁹ a¹⁰.

Between the tables a⁹ and a¹⁰ is a gate B, Figs. 9, 10, 11, composed of two steel plates b and b', arranged to slide longitudinally one upon the other in opposite directions. The plate b rests upon one end of the plate b', which is slightly depressed, so that the upper surfaces of the two plates are on a level with each other. The plate b' has a rectangular opening through it somewhat larger than the links of the chain a⁷ and has a rack b² secured face upward to one end. A rack b³ is secured face downward to the plate b. A pinion b⁴ upon a stud projecting from a hanger b⁵ engages the racks b² b³ in such manner that when one of the racks is moved the other moves in the opposite direction. Fig. 10 shows the gate B closed, the dotted line s showing the position of a can-body resting upon the plates b b'. Fig. 11 shows the gate B opened to allow the can-body s to drop through the gate. The gate B is opened and closed by the lever b⁶, which engages a pin b⁷ upon the side of the rack b³. The lever b⁶ is pivoted to an arm b¹⁰, attached to the frame of the machine, and is provided with a cam-groove b⁹, engaged by a pin and roller b⁸, secured in an arm b¹¹, projecting from the face of the ram A⁸.

Directly below the gate B and in vertical alinement with the center line of the ram A⁸ is placed a chuck C, Figs. 6 and 7, which has in its upper face four converging channels in the form of a Greek cross. In each of these channels is a sliding jaw c, carrying on its inner end a die-holder c⁵, to which is secured a die c⁶. The dies c⁶ are made with their inner faces exactly fitting the outside of the can-body to be operated upon and of a height equal to the distance between the flanges of

the can and constitute when the flanges of the body are turned outward anvils around which the flange is turned. Each of the jaws c has in its under side a transverse rectangular slot 5 c' , in which is a sliding block c^4 , engaged by a crank c^3 on the upper end of a pinion c^2 , journaled in the body of the chuck.

A cam d , secured to the side of the gear A^5 , acts upon a pin and roller (shown in Fig. 19) 10 upon the side of a cam-rod d' , which terminates in a rack which engages a segment-gear d^2 upon a rock-shaft d^3 , journaled in suitable hangers $d^4 d^5$, secured to the table A' . Segment-gears $d^6 d^6$, secured to the rock-shaft d^3 , 15 engage racks $d^7 d^7$, each of which engages two of the crank-pinions c^2 of the chuck C . The movement of the racks d^7 is equal to one-half the pitch-circumference of the pinions c^2 , and the pinions are so placed in relation to the 20 racks that at one extremity of their motion the chuck C is closed, as in Fig. 6, and at the other extremity of their motion the chuck C is opened, as in Fig. 7. When the chuck C is closed, the dies c^6 exactly fit the outside of 25 the can-body.

Referring to Figs. 2, 4, and 8^a, the ram A^8 is provided with projections $e e$, which when the ram is nearly at the extremity of its downward motion strike and depress a lever e' , 30 pivoted in the back of the frame A . The lever e' rests upon a post e^2 , supported by one end of a horizontal lever e^3 , pivoted upon the end of an adjusting-screw e^4 in the lower part of the frame A . The bottom of the ram e^5 35 rests upon the point of the lever e^3 and is held downward by a compression-spring e^6 upon a rod e^7 , screwed into the ram e^5 . The ram e^5 slides in a vertical opening in the middle of the chuck C and has secured to its upper face 40 the bottom die f .

The ram A^8 is bored to receive and hold the shank of a die-holder f' , to the lower face of which is secured the top die f^2 . The dies $f f^2$, Figs. 12, 13, are each provided with a flange 45 f^3 , the flange and body of the die being made of one piece and the corner between body and flange being rounded so that when the dies approach each other, as in Fig. 12, the rounded corners will bend the edges of the can-body s 50 over the corners of the die f^6 , and the flanges f^3 will press the said edges against the horizontal faces of the die f^6 , as shown in Fig. 13, leaving the can s flanged, as in Fig. 14. The die-holder f' and die f^2 are provided with 55 three dovetailed grooves, into each of which is loosely fitted a stripper g , Figs. 8^a, 15, 16. The lower ends of the strippers are made to fill the grooves through the flange f^3 , so as to continue the face of the flange unbroken. The 60 upper ends of the strippers g are provided with transverse notches into which fits a yoke g' , which is provided with a hollow shank g^2 , which slides in a suitable projection g^3 in the rear of the ram A^8 . A spring g^4 , secured in 65 the hollow shank g^2 and attached to a hook g^5 ,

projecting from the ram A^8 , serves to hold the yoke g' in place. As the ram A^8 rises the yoke g' strikes the forked lever e' and stops, holding the strippers stationary and preventing the further rise of the can while the die f^2 is withdrawn from the can. As the ram A^8 descends the spring g^4 holds the yoke and strippers stationary until the strippers are struck by the face of the ram, when all move together through the remainder of the stroke. 75

In operation the can-bodies are placed on end in the links of the chain at the right side of the machine, Fig. 1, and by continuous motion of the chain are carried forward and placed upon the gate B . As the chain pauses the 80 gate B opens and allows the can-body to fall into the chuck C , the gate B thus forming a trap in the table. The dies of the chuck C move together toward the can while the top die f^2 enters it and then close lightly upon it. 85 When the top die reaches the position shown in Fig. 12, the bottom die begins to rise and both dies close upon the can, as in Fig. 13. The chuck C then opens and the ram A^8 rises with the can held by friction upon the body of die f^2 . 90 When the can has risen sufficiently to clear the gate B , the gate closes and the can is stripped from the die f^2 and falls into the chain and upon the gate B . The chain then moves along, carrying the flanged can-body 95 with it, while it places another body upon the gate ready for flanging.

What I claim, and desire to secure by Letters Patent, is—

1. In a machine of the class described, the 100 gate B consisting of the plates b and b' arranged to slide one upon the other with means for giving said plates longitudinal motion in opposite directions so as to lengthen or shorten the space inclosed between the inner edges of 105 said plates.

2. In a machine of the class described the gate B consisting of a plate b' having its interior portion cut away and a plate b arranged to slide longitudinally across the opening in 110 said plate, with means for giving said plates reciprocating longitudinal motion in opposite directions so as to lengthen or shorten the space between the inner edge of said plate b and the opposite side of said opening, substantially as described. 115

3. In a machine of the class described the gate B consisting of the plates b and b' arranged to slide longitudinally one upon the other in combination with the racks $b^2 b^3$ attached to 120 said plates, pinion b^4 engaging said racks, and means for giving to one of said plates reciprocating longitudinal motion, substantially as described.

4. In a machine of the class described the 125 gate B consisting of the plates b and b' arranged to slide longitudinally one upon the other, racks $b^2 b^3$ attached to said plates, pinion b^4 engaging said racks and means for giving 130 said plate b longitudinal reciprocating

motion consisting of the lever b^6 pivoted at its lower end to said plate b and at its upper end to a projection upon the frame A, pin and roller b^8 working in the cam-groove b^9 in the 5 face of said lever b^6 and mounted upon the projection b^{11} on the vertically-moving ram A⁸, substantially as described.

5. In a machine of the class described tables a^9 , a^{10} , gate B between said tables consisting 10 of the plates b and b' arranged to slide longitudinally one upon the other, and means for opening and closing said gate, in combination with the feed-chain a^7 and means for giving the same intermittent progressive motion, 15 substantially as described.

6. In a machine of the class described the feed-chain a^7 with means for giving the same intermittent progressive motion, tables a^9 , a^{10} , gate B between said tables, with means 20 for opening and closing the same, and chuck C placed under said gate and adapted to receive and hold a can dropped through said gate B, substantially as described.

7. In a machine of the class described, the 25 chuck C having in its upper face four converging channels whose middle lines cross at a right angle with each other, jaws c sliding in said channels and having die-holders c^5 bolted thereto, each jaw having in its under 30 side a transverse slot c' , and a block c^4 adapted to slide therein, a shank-pinion c^2 journaled in the body of the chuck C under each of the jaws c , and having a crank-pin in its upper end engaging with the block c^4 in the jaw 35 above it, racks d^7 each engaging two of the pinions c^2 and means for giving said racks reciprocal motion, substantially as described.

8. In a machine of the class described a 40 chuck C, having four die-carrying jaws sliding in converging channels in its upper face each jaw being operated by a shank-pinion c^2 journaled in the body of the chuck and having on its upper side a crank-pin engaging a block sliding in a transverse groove in the 45 under side of said jaw, said pinions being moved in pairs by racks d^7 engaging therewith, in combination with means for giving

said racks reciprocal motion consisting of the segment-gears d^6 engaging said racks and mounted upon a rock-shaft d^3 carrying a segment-gear d^2 engaged by a rack upon a cam-rod d^7 operated by the cam d , substantially as described. 50

9. In a machine of the class described the feed-chain a^7 mounted upon sprocket-wheels a^8 with the described means for giving the same intermittent progressive motion consisting of a barrel-cam a^5 engaging rollers a^6 mounted upon and carried by the side of said chain and means for giving rotary motion to 60 said cam, substantially as described.

10. In a machine of the class described having a chuck C with dies c^6 and vertically-reciprocating dies f , f^2 co-operating with said dies c^6 in forming flanges upon the ends of a 65 can, means for effecting the conjoint action of the dies f , f^2 upon the opposite ends of the can consisting of the ram A⁸, carrying the die-holder f' and die f^2 with means for giving said ram reciprocating vertical motion, projections e upon said ram engaging the lever e' , connecting-rod e^2 for transmitting the motion of the lever e' to one end of the lever e^3 , die-carrier e^5 resting upon the opposite end of said lever e^3 and spring e^6 connected with said 70 carrier e^5 , all substantially as described.

11. In a machine of the class described the die-holder f' and flanged die f^2 , f^3 attached to the vertically-reciprocating ram A⁸ in combination with means for removing a flanged 80 can from said die consisting of strippers g projecting downward through grooves in said die-holder and die-yoke g' attached to said strippers, spring g^4 connecting said yoke with the ram A⁸ and forked lever e^2 engaging said 85 yoke, substantially as described.

In testimony whereof I have hereunto subscribed my name in the presence of two witnesses.

CHARLES W. SLEEPER.
